(57) **CLAIM**

The ornamental design for a combined induction hub and immersion heater, as shown and described.

DESCRIPTION

FIG. 1 is a perspective view of a combined induction hub and immersion heater showing our new design;
FIG. 2 is a front elevational view thereof;
FIG. 3 is a back elevational view thereof;
FIG. 4 is a right side elevational view thereof;
FIG. 5 is a left side elevational view thereof;
FIG. 6 is a top view thereof;
FIG. 7 is a bottom view thereof;
FIG. 8 is a perspective view of the combined induction hub and immersion heater of FIG. 1 illustrating use with a mug; and,
FIG. 9 is a top view thereof.
The broken lines shown in the drawings are for illustrative purposes only and form no part of the claimed design.

1 Claim, 9 Drawing Sheets
